UNITED STATES PATENT OFFICE

PRINCE A. GARDNER, JR., OF UNIVERSITY CITY, MISSOURI

BILL FOLD

Application filed May 10, 1929. Serial No. 361,947.

This invention relates to bill folds and comprises a receptacle for currency foldable intermediate of its ends and having the inner wall or panel arranged in a novel co-operative relationship to the outer wall or cover so that the inner wall or panel will fold smoothly and will not buckle when the device is folded.

Another object of the invention is to provide a bill fold or receptacle comprising several known equivalent variations of the bill fold or receptacle constituting the subject matter of my prior application for patent for bill fold or receptacle filed April 18, 1929, 15 Serial No. 356,005.

Other objects will appear from the following description, reference being made to the accompanying drawings in which

Fig. 1 is an inside view of the bill fold extended or unfolded.

Fig. 2 is a similar view with portions of the walls of the end pockets removed to show the inner panel and an appropriate means for securing the inner panel in proper position.

Fig. 3 is a longitudinal diagrammatic sectional view approximately on the line 3—3 of Fig. 1.

Fig. 4 is a diagrammatic cross sectional view approximately on the line 4—4 of Fig. 1.

Fig. 5 is a diagrammatic sectional view approximately on the line 5—5 of Fig. 1.

Fig. 6 is a view of the inner panel detached from the other elements of the bill fold.

Fig. 7 is an inside view of a bill fold of modified construction showing portions of the walls of the end pockets removed to show the inner panel and an appropriate means for securing the inner panel in proper position.

Fig. 8 is a diagrammatic longitudinal sectional view on the line 8—8 of Fig. 7.

Fig. 9 is a view showing the side of the inner panel that is toward the outer panel, said panel being turned to position in which the ends are opposite from the ends shown in Fig. 7.

Fig. 10 is a diagrammatic cross sectional view on the line 10—10 of Fig. 7.

Fig. 11 is a diagrammatic cross sectional view on the line 11—11 of Fig. 7.

Fig. 12 is an inside view of another variation of the bill fold showing the bill fold extended and with portions of the walls of one 55 of the end pockets removed to disclose other parts.

Fig. 13 is a diagrammatic view showing the inside of the outer cover or back of the bill fold satisfactory for use in any of the embodiments herein disclosed.

Fig. 14 is a diagrammatic longitudinal sectional view on the line 14—14 of Fig. 12.

Fig. 15 is a diagrammatic cross sectional view on the line 15—15 of Fig. 12. 65

Fig. 16 is a diagrammatic cross sectional view on the line 16—16 of Fig. 12.

Fig. 17 is a view showing the side of the sliding panel that is toward the outer cover or back of the bill fold.

Fig. 18 is an inside view of a bill fold of modified construction with portions of the walls of the end pockets removed to show other features of the device.

Fig. 19 is a diagrammatic longitudinal sectional view on the line 19—19 of Fig. 18. 75

Fig. 20 is a diagrammatic cross sectional view approximately on the line 20—20 of Fig. 18.

Fig. 21 is an inside view of another variation of the device with portions of the walls of the end pockets broken away to disclose other features.

Fig. 22 is a diagrammatic longitudinal sectional view on the line 22—22 of Fig. 21. 80

Fig. 23 is a diagrammatic cross sectional view on the line 23—23 of Fig. 21.

In the embodiment of the invention shown in Figs. 1 to 6, inclusive, my improved bill fold or receptacle comprises a section 1 of 90

flexible material such as leather or other materials adapted for these uses and made of a size sufficient to form the outside of the bill fold. Against the inner side of the section 1 two separate end members 2 and 3 are laid 95 and have their outer or end edges even with the end edges of the member 1 and their lower edges approximately even with the lower longitudinal edge of the member 1. The member 2 is folded outwardly upon itself along a 100

fold line 4 which is slightly below the upper edge of the member 1. The outer folded portion of the member 2 as shown is cut out to form an open frame 5, the opening through 5 which is closed by transparent window 6. Either or both sides of the member 1 may be finished or either side may be unfinished and have a finished surface forming member affixed thereto. The end and lower edges of 10 the member 2 and also the end and lower edges of the frame 5 are attached to the member 1 by fastening means such as stitches 7.

The member 3 is folded outwardly upon itself along a line 8 which is slightly below 15 the upper edge of the member 1 and in longitudinal alinement with the upper edge 4 of the member 2. The outer end and lower longitudinal edges of the member 3 and the outwardly folded portion 9 thereof are attached 20 to each other and to the member 1 by suitable fastening means as by stitches 10.

A pocket forming partition 11 is mounted for sliding movements in the pocket 12 formed by the folded portions 3 and 9. The 25 member 11 is flexible but is characterized by sufficient stiffness so that it may be easily pushed back into the pocket without folding or buckling after having been withdrawn. A piece of flexible material 13, which may 30 be made of a piece of cloth, has its inner portion folded to enclose the inner end of the member 11 and has its end edge attached to said member 11 by fastening means 14, which may be glue. The member 13 extends 35 outwardly to attachment at 15 with a resilient member 16 mounted on the inside of the part 9 and having its outer edge attached thereto by stitches 17. The outer end of the member 11 is extended to provide 40 a tab 18 which may be folded to close the pocket 19 formed between said member and the parts 13 and 16. A tongue and loop device 20 is provided for holding the tab 18 in closed position. A foldable panel 21 has 45 its edge extending into the pocket 22 between the member 2 and the frame and window devices 5—6. The panel 21 is attached to the edge of the member 22 by fastening means 23. The panel 21 extends across the fold line 50 of the device and into the pocket between the member 3 and the member 11. To the end of the panel 21 a flexible section 24 of cloth or the like extends to the end of the device and is engaged and secured by the stitches 55 10. It is plain enough that when the device is folded and irrespective of the number of pieces of currency or papers that may be contained in the pocket formed between the member 1 and the members 2 and 3, the panel 60 21 will fold properly and will not buckle because it is freely slidable.

In the variation of the invention shown in Figs. 7 to 11, inclusive, the bill fold comprises an outer section of appropriate flexible 65 material 25 forming the outer wall of a long

pocket 26. To one end and to the lower longitudinal edge of the member 25 a wall forming member 27 is attached by stitches 28. The wall forming member 27 is folded outwardly to provide an outer wall 29, the 70 end and lower longitudinal edge of which are engaged by the stitches 28. Between the walls 27 and 29 a pocket forming wall 30 is secured, the end thereof being engaged by the stitches 28 at the end of the device. 75 The outer end of the member 30 is extended to provide a foldable tab 31 equipped with a tongue 32 for engagement with a loop 33 on the outer side of the wall 29.

To the opposite end of the member 25 a 80 wall forming panel 34 is attached by stitches 35. The opposite end of the panel 34 extends between the members 27 and 30 and has its ends connected with a foldable section 36 of fabric or the like which is engaged and 85 secured by the stitches 28 at the end but not along the lower marginal edge.

A frame 37 is engaged by the stitches 35 at its outer end and by a row of stitches 38 at its inner end and by stitches 39 at its 90 lower longitudinal edge which are a continuation of the stitches 35 and 38. The stitches 39 also engage the lower edge of the panel 34. This leaves a pocket 40 formed between the panel 34 the frame 37 and the transparent 95 window 41 which is attached to said frame.

In the variation of the invention shown in Figs. 12 to 17, inclusive, the bill fold comprises a section 42 forming the outside of the bill fold. To one end of and to the lower 100 longitudinal edge of the member 42 a wall forming member 43 is secured by stitches 44 and is folded outwardly upon itself to provide an outer wall 45. A pocket wall forming member 46 extends between the parts 43 and 45 and has its end engaged by the 105 stitches 44 at the end of the device and is provided on its outer end with a foldable tab 47 equipped with a tongue 48 for engagement with a loop 49 on the member 45.

A panel comprising a narrow inner end portion 50 and a wide end portion 51 has the wide outer end portion thereof attached to the inner side of the member 42 by stitches 52 running across the end of the wide portion 51 and across the lower longitudinal edge thereof but leaving the upper edge of said panel detached so as to form an open pocket 53. The inner end of the narrow portion 50 of this panel projects for free sliding movements between the members 43 and 46 so as to permit the bill fold to be folded without buckling the part 50. A frame 54 is engaged by the stitches 52 and has its inner end secured to the panel portion 51 by stitches 55, leaving the upper edge of said frame detached. A transparent window 56 is secured in the frame 54 and cooperates therewith to form a pocket 57.

In the variation of the invention shown 130

in Figs. 18, 19 and 20 an outer section 58 has attached to one end thereof a wall forming member 59. This member 59 is folded outwardly upon itself to provide a wall 62, 5 the outer end and lower longitudinal edges of which are attached to the member 58 and 59 by stitches 60. A wall forming member 63 projects between the folds 59 and 62 and is engaged by the stitches 60 at the end of 10 the device. The inner end of the member 62 is folded to form a tab 64 equipped with a tongue 65 for engagement with a loop 66 on the wall 62.

A panel 67 is secured to the opposite end 15 of the member 58 by stitches 68 which also secure the lower longitudinal edge of the panel 67 to the lower longitudinal edge of the member 58 for a portion of the length of the panel 67. A pocket forming wall 69 is 20 laid against the outer side of the panel 67 and is engaged by the stitches 68 along its outer end and lower longitudinal edge, and by stitches 70 along its inner end, leaving the upper edge of said part 69 detached to 25 form a pocket between said part 69 and the panel 67. A frame 71, having a transparent window 72 therein, has its edges engaged by the stitches 68 and 70 leaving the upper edge of said frame detached to form an open 30 pocket.

The opposite end of the panel 67 extends between the walls 59 and 63 and is connected with the end of the bill fold by a flexible member 73 engaged by the stitches 60 at the 35 end of the device but not along its lower marginal edge. Thus the panel 67 is free to slide so that it will not buckle when the device is folded.

In the variation shown in Figs. 21 to 23, 40 inclusive, the outer section 74 has attached to one end thereof a wall forming member 75 which is folded outwardly at its upper edge to provide an outer wall 76. The outer and lower longitudinal edges of the parts 75—76 45 are engaged and secured to the member 74 by stitches 77. Between the walls 75—76 a wall forming member 78 is located and has its outer end engaged by the stitches 77.

The inner end of the member 78 is extended 50 to form a foldable tab 79 having attached thereto a tongue 80 for engagement in a loop 81 secured on the outer side of the wall 76.

To the opposite end of the member 74 a wall forming member 82 is secured and is 55 folded outwardly upon itself to provide an open frame 83. The outer end and lower longitudinal edges of the parts 82 and 83 are attached to each other and to the member 74 by stitches 84, leaving the inner ends 60 of the parts 82 and 83 detached to form an open pocket 85. To the inner end of the member 82 a wall forming panel 86 is secured by fastening means 87, and the opposite end of said panel 86 extends into the 65 pocket between the walls 75 and 78 and is free-

ly slidable therein. It is plain that when the device is folded, the panel 86 will slide into the space between the walls 75 and 78 and will not buckle but will fold smoothly with the outer member 74. 70

Other variations of my invention might well be devised without departure from the nature and principle thereof. I do not restrict myself unessentially but what I claim and desire to so secure by Letters Patent is: 75

1. A bill fold comprising an outer wall member, two pocket wall members each less than one-half the length of said outer wall member folded downwardly and outwardly upon themselves and each having its outer and lower longitudinal edges secured to an end and the lower longitudinal edge of said outer wall member and each forming an inwardly open pocket, an additional wall member having one end secured to the inner end 80 of one of said pocket wall members and having its opposite end telescoping in the opposite pocket, and a flexible element connecting the telescoped end of said last named wall member with the outer end of said pocket. 85

2. A bill fold comprising an outer wall member, a pair of pocket wall members each less than one-half the length of the outer wall member and folded downwardly and outwardly upon themselves and each having 90 its outer and lower longitudinal edges secured to an end and to the lower longitudinal edge of said outer wall member and each forming an inwardly open pocket, an additional wall member of less width than the other of 95 said wall members having one end attached to the inner end of one of said pocket wall members and having its opposite end extending into the other pocket and terminating short of the bottom of said pocket, and a 100 flexible element connecting said additional wall member with the bottom of said pocket into which said additional wall member extends. 105
